UNITED STATES PATENT OFFICE

1,989,504

CORNER BEAD FASTENER

Isaac A. Baum, Chicago, Ill., assignor to Kalman Steel Company, Chicago, Ill., a corporation of Delaware

Application July 22, 1929, Serial No. 380,210

8 Claims. (Cl. 72—121)

My invention relates to building construction and particularly to a novel method and means for attaching plaster corner beads to masonry or similar walls.

Difficulty has always been experienced in attaching the usual and necessary corner beads to tile, brick or concrete walls. Various expedients have been adopted, none of which are entirely satisfactory. The idea here disclosed enables a firm and rigid attachment of the corner bead at very low cost and without the use of any special tools. It consists essentially of a wire anchor, preferably composed of two pieces of wire, the body of which is embedded in the mortar or other plastic material, and the ends of which project from the faces of the masonry.

The invention will be more readily understood by reference to the accompanying drawing, in which

Fig. 1 is an elevation or face view of a corner bead applied as here disclosed; and

Fig. 2 is a sectional view therethrough.

In the drawing, I have illustrated a wall at 10, in this instance composed of tile or brick, the adjacent courses being separated by mortar joints indicated at 11. The corner bead may be of any desired construction, the one illustrated consisting of a section of sheet metal bent to provide apertured base portions 12 and a bead portion 13. The base portion is intended to fit snugly against the faces of the wall at the angle.

The anchoring device consists of two lengths of wire one of which has a loop 13 formed therein, and the other of which is preferably straight as at 14. The two wires are twisted together or otherwise joined for convenience in handling. As originally installed, the free ends 15—16 are parallel and project beyond the faces of the wall as indicated in dotted lines in Fig. 2. The said ends may be bent parallel to the faces of the wall to prevent obstruction and the parts remain in this condition until the mortar has hardened. When the corner bead is to be installed, one of the wire ends is projected through an aperture in the base of the bead and the two ends twisted together as indicated. The twisted ends are hammered down to insure a minimum projection, and after the plaster indicated at 17 has been applied, the wires are covered. It will be understood of course that the wire anchors are laid in the mortar during the process of building the wall, or in the case of a concrete wall they may be nailed or stapled to the forms and the concrete poured leaving the anchors embedded therein.

Obviously the exact form of the anchor is

unimportant and changes in the construction thereof may be made without departure from the spirit of my invention.

I claim:

1. A fastener for securing corner beads to masonry walls consisting of a pair of wires one wire being bent to provide a loop adapted to act as an anchor in mortar, the other wire being parallel thereto at the free ends of the wires the middle thereof lying opposite said loop, the pairs of free ends being adapted to project beyond the two faces of the wall at the corner angle. 5

2. A fastener for securing corner beads to the corner of a masonry wall, which consists of a pair of wires, one wire being bent into a loop at its middle and adapted to act as an anchor in mortar, the other wire being substantially parallel to said first wire except at the loop and engaging said wire on opposite sides of the loop, 15 and also acting as an anchor, the free ends of the pairs of wires being adapted to project beyond the masonry wall across the corner thereof. 20

3. A fastener for corner beads wherein the corner bead is fastened to the corner of a masonry wall by tying the same on the two sides thereof with the extremities of a pair of anchor wires, which consists of a pair of wires, one of which is bent into a loop at its middle and the other being wound around the legs of the wire adjacent the loop of the first wire, the extremities of said wires projecting outside of the masonry wall on adjacent sides of the corner thereof. 25 30

4. An anchor for securing metallic corner beads to the corner of a built up masonry wall, which consists of a pair of wires wound around each other adjacent both ends and having portions intermediate their ends in spaced relation to each other, a substantial portion of the length thereof being embedded in the mortar between courses, 40 and the opposite free ends extending beyond the adjacent faces of said wall and across the corner thereof. 35

5. A fastener for securing corner beads to masonry walls comprising a member adapted to extend diagonally across the corner of the wall with its ends projecting beyond the faces thereof adjacent the corner of the wall and a cooperating member offset intermediate the ends of the first-mentioned member adapted to extend inwardly 50 from the corner of the wall to provide an anchor in the mortar to retain said fastener against lateral displacement. 45

6. In combination with a wall, a corner bead embracing a corner of said wall, retaining means 55

for said bead, said means comprising a member having its body portion embedded within said wall diagonally across the corner thereof and its ends projecting beyond the faces of said wall a distance from said corner and engaging the legs of the corner bead.

7. In combination with a wall, a corner bead having flanges engaging the sides of the wall adjacent a corner thereof and retaining means for 10 said bead extending diagonally through said corner and engaging the flanges of said bead whereby the flanges of the bead are connected a distance

inwardly from the corner of the wall and retained in rigid contact with said wall.

8. In combination with a wall, a corner bead embracing a corner of said wall, retaining means for said bead, said means comprising a member having an offset body portion embedded within said wall a distance from the corner thereof and its ends projecting beyond the faces of said wall a distance from said corner and engaging the legs of the corner bead.

ISAAC A. BAUM.

CERTIFICATE OF CORRECTION.

Patent No. 1,989,504.

January 29, 1935.

ISAAC A. BAUM.

It is hereby certified that error appears in the printed specification of the above numbered patent requiring correction as follows: Page 1, second column, line 38, claim 4, for "spared" read spaced; and that the said Letters Patent should be read with this correction therein that the same may conform to the record of the case in the Patent Office.

Signed and sealed this 25th day of June, A. D. 1935.
